CLAIM

The ornamental design for a ceiling fan motor housing, as shown and described.

DESCRIPTION

FIG. 1 is a top perspective view of a ceiling fan motor housing in the environment of a ceiling fan showing my new design;

FIG. 2 is a bottom perspective view of the ceiling fan motor housing of FIG. 1;

FIG. 3 is a top perspective view of the ceiling fan motor housing of FIG. 1;

FIG. 4 is a bottom view of the of the ceiling fan motor housing of FIG. 1;

FIG. 5 is a top view of the ceiling fan motor housing of FIG. 1; and,

FIG. 6 is a side view of the ceiling fan motor housing of FIG. 1.

The broken lines depict portions of the ceiling fan motor housing that form no part of the claimed design. The additional broken lines in FIG. 1 depict ceiling fan environmental subject matter and form no part of the claimed design.

1 Claim, 5 Drawing Sheets
